UNITED STATES PATENT OFFICE.

FRANK R. RUSH, OF JAMESTOWN, NEW YORK.

NECKTIE-STRETCHER.

1,330,010.

Specification of Letters Patent. Patented Feb. 3, 1920.

Application filed April 9, 1919. Serial No. 288,731.

To all whom it may concern:

Be it known that I, FRANK R. RUSH, a citizen of the United States, residing at Jamestown, in the county of Chautauqua, 5 State of New York, have invented a new and useful Necktie-Stretcher; and I do hereby declare the following to be a full, clear, and exact description of the invention, such as will enable others skilled in the art to 10 which it appertains to make and use the same.

The present invention relates to an improved necktie stretcher, and has for its object to provide a device of this character 15 which embodies novel features of construction whereby it can be readily inserted in the flared ends of a four-in-hand tie or the like and will hold the same in a stretched condition when not in use, thereby removing all 20 wrinkles therefrom and enabling the tie to be kept in perfect condition.

Further objects of the invention are to provide a necktie stretcher which can be inexpensively formed from a single length 25 of wire, which can be quickly placed in position or removed therefrom, which can not injure the necktie in any manner, and which will effectively stretch the ends of a four-in-hand tie in such a manner as to remove the 30 wrinkles therefrom.

With these and other objects in view, the invention consists in certain novel combinations and arrangements of the parts as will more fully appear as the description proceeds, the novel features thereof being 35 pointed out in the appended claim.

For a full understanding of the invention, reference is to be had to the following description and accompanying drawings, in 40 which:

Figure 1 is a plan view of a necktie stretcher constructed in accordance with the invention.

Fig. 2 is a side elevation thereof.

Fig. 3 is a perspective view showing the stretcher as applied to a four-in-hand tie.

Corresponding and like parts are referred to in the following description and indicated in all the views of the drawings by the same 50 reference characters.

The scarf or necktie stretcher can be inexpensively formed from a single length of spring wire, and includes a pair of stretching elements A and B which are suitably 55 formed to engage the flared ends of a four-in-hand tie such as that indicated at C.

The stretching element A includes a pair of creasing arms 1 which have a flat formation and are straight, said creasing arms being flared and connected at their converging ends by a spring bow 2. In a similar manner the stretching element B is formed of a pair of diverging creasing arms 3 which are straight and have a flattened formation, the converging ends of the arms being connected 60 by a resilient bow 4. The creasing arms 3 of the stretching element B are longer than the arms 1 of the stretching element A, and are arranged at a smaller angle, the element B being adapted to be inserted in the large 65 end of a four-in-hand tie, and the stretching element A into the small end of the tie, as indicated by Fig. 3. The two stretching frames A and B are preferably arranged in a superposed and spaced relation, corresponding arms of the stretching frames being connected at one side of the device by an integral arched arm 5, while the free 70 ends of the creasing arms at the opposite side of the device are provided with laterally deflected finger pieces 6. The device can be readily formed from a single piece of spring 75 wire, those portions of the wire which form the creasing arms being flattened so that they will have comparatively sharp edge 80 portions adapted to engage the folded portions of the fabric and form creases therein. This flattening of these creasing arms also stiffens the same so that they will not 85 bend and deflect the creasing edges from a straight line. The flared ends of a necktie can be readily pulled on the respective stretching elements A and B, the creasing arms of the respective stretching elements being sprung inwardly toward each other 90 to accommodate the tie, and the resiliency of the body elements 2 and 4 holding the creasing arms in a spring engagement with the folded portions of the tie fabric so that the tie will be maintained in a stretched 95 condition, thereby effectively removing all wrinkles and creases therefrom. A four-in-hand tie can thus be preserved in a most effective manner, and the curved connecting arm 5 may be utilized for hanging the stretcher from a nail or the like, if such is desired.

Having thus described the invention, what I claim as new and desire to secure by Letters Patent, is:

A device for simultaneously stretching both ends of a necktie, said device being

formed of a single length of resilient wire and including a pair of stretching elements arranged in spaced and parallel planes, each stretching element comprising a pair of diverging creasing arms which are connected at their converging ends by integral resilient bows, the stretching elements being adapted to be inserted in the two flared ends of a four-in-hand tie and the free end of one creasing arm of each stretching element terminating in a finger piece, while the outer

ends of the other creasing arms are connected by an integral resilient bow, the several creasing arms being flattened in the planes of the respective stretching elements.

In testimony whereof I have signed my name to this specification in the presence of two subscribing witnesses.

FRANK R. RUSH.
